UNITED STATES PATENT OFFICE.

ELLA JANE FREEMAN, OF BOSTON, MASSACHUSETTS.

DESIGN FOR A SINK GUARD OR STRAINER.

SPECIFICATION forming part of Design No. 30,746, dated May 9, 1899.

Application filed April 13, 1899. Serial No. 712,938. Term of patent 7 years.

To all whom it may concern:

Be it known that I, ELLA JANE FREEMAN, a citizen of the United States, residing at East Boston, in the county of Suffolk and State of Massachusetts, have invented and produced a new and original Design for Sink-Guards, of which the following is a specification, reference being had to the accompanying drawing, forming part thereof.

The accompanying drawing represents a perspective view of the new design for a sink guard or strainer.

As illustrated in the drawing, the leading or material feature of the design consists of a ring or annulus 1, provided at suitable intervals with upwardly-extending hangers or fingers 2, having their extremities bent outward radially and away from each other, as at 3, the extremities 3 being in a common plane, which is substantially parallel to the plane of the ring or annulus 1. Depending

from the ring or annulus 1 is a somewhat cylindrical guard or receptacle 4, having a hemispherical lower end 5. The body of the receptacle 4 is shown as composed of meshed-wire fabric, and the bottom, which is integral therewith, is formed of the same material. The body 4 of the receptacle is shown as attached along its upper edge to the ring or annulus 1. 25

Having described the invention, what is claimed as new, and desired to be secured by Letters Patent, is— 30

The design for a sink guard or strainer as herein shown and described. 35

In testimony whereof I affix my signature in presence of two witnesses.

ELLA JANE FREEMAN.
